UNITED STATES PATENT OFFICE.

WILLIAM L. OCHS, OF NEW YORK, N. Y.

POLISHING AND CLEANING MITTEN.

Application filed October 16, 1923. Serial No. 668,918.

To all whom it may concern:

Be it known that I, WILLIAM L. OCHS, a citizen of the United States, and a resident of the city of New York, borough of Manhattan, in the county and State of New York, have invented a new and Improved Polishing and Cleaning Mittens, of which the following is a full, clear, and exact description.

10 This invention relates to cleaning and polishing devices and particularly to an improved cleaning and polishing mitten which may be worn as an article of clothing to keep the hands warm whenever desired or 15 may be used as one or two polishing articles.

The object of the invention is to provide an improved combination article which may readily be used as an article of clothing, as one cleaning and polishing member or as a 20 double cleaning and polishing member.

Another object of the invention is to provide an improved mitten structure which may be quickly and readily connected and disconnected so that it may be used as a 25 mitten for keeping the hands warm at one time and used as a pair of cleaning and polishing members at another time.

In the accompanying drawing—

Figure 1 is a plan view of a mitten in assembled condition.

Figure 2 is a longitudinal vertical section through Figure 1, the same being on an enlarged scale.

Figure 3 is a plan view of one-half of the 35 mitten shown in Figure 1, the same being viewed from the interior.

Figure 4 is a view similar to Figure 3 but showing the other half of the mitten, with a modified form of strap.

40 Referring to the accompanying drawing numerals 1 and 2 indicate the two sections of a mitten, each section of which is provided with a body 3 merging into a thumb member 4. Each section is provided with a strap 5 beneath which the fingers of the hand may be placed when the section is to be used as a cleaning or polishing article. The straps 5 may be held in place by any suitable means, as for instance, lines of stitching, said straps being formed of fabric, rubber, leather or any other desired material.

45 In Figure 4 of the drawing, a strap 5' functions in a similar manner to strap 5 shown in Figure 3 but extends over the entire body of the glove so that it may act as

a covering member for the hand when half of the glove is used as a mitten. It will also be evident that the thumb may be eliminated if desired and yet the device function 60 properly for cleaning or even for covering the hands. The body 3 of the respective sections of the mitten, is shown in the drawing as formed from sheepskin with the wool 65 still adhering thereto but if preferred, canvas or other material might be used with an artificial wool or fleecing connected therewith. Ordinarily, the parts of the mitten are made from sheepskin with the wool still 70 adhering thereto as the same is comparatively inexpensive and also very effectively operates in cleaning and polishing automobiles, furniture or other articles while at the same time presenting an extremely desirable 75 structure for cold weather.

The sections 1 and 2 are connected together in any desired manner provided the connection may be readily engaged and disengaged from time to time. In the accompanying drawing, suitable snap fasteners 8 80 are provided whereby the sections may be snapped together and held in position to function as a mitten and also may be readily pulled apart without injury to the sections or the fastening means.

If desired, the sections could be maintained together as shown in Figures 1 and 2 and opposite sides used while in that position. For instance, one side could be used for applying cleaning matter and the other 90 used merely in polishing. However, in operating on comparatively large surfaces, as for instance, large pieces of furniture or automobile bodies, it is desired to use both hands during the cleaning and polishing 95 operation and, consequently, the parts are preferably separated as shown in Figures 3 and 4 and one part applied to each hand so that the efficiency of the workman will be greatly increased.

100 What I claim is:—

1. A cleaning and polishing mitten, comprising a complete mitten structure formed in two independent parts, means for disengagably connecting said parts together, and 105 means connected to each part for forming a retaining strap for the hands when the parts are used separately.

2. A cleaning and polishing mitten, comprising a mitten structure formed in two 110 parts, each part having a body of leather with the natural wool projecting from one

surface of the leather, means for disengageably connecting said parts together, and means presenting retaining structures for holding the respective parts on a hand when the parts are being used separately.

3. A cleaning and polishing mitten, comprising a mitten structure formed in two independent parts, means for disengageably

connecting said parts together, and means connected to each part forming a retaining strap for the hands when the parts are used separately, said strap extending from substantially one end to the other of the respective parts. ¹⁰

WILLIAM L. OCHS.
